CLAIM

We claim the ornamental design for a showerhead, as shown and described.

DESCRIPTION

FIG. 1 is a left side perspective view of a showerhead in accordance with the present invention;

FIG. 2 is a front elevational view of the showerhead in accordance with the present invention;

FIG. 3 is a right side elevational view of the showerhead in accordance with the present invention, with the left side elevational view being the mirror image thereof; and
FIG. 4 is a back elevational view of the showerhead in accordance with the present invention;

FIG. 5 is a top elevational view of the showerhead in accordance with the present invention; and,

FIG. 6 is a bottom elevational view of the showerhead in accordance with the present invention.

The broken line showing in FIG. 6 is included for the purpose of illustrating and forms no part of the claimed design.
